UNITED STATES PATENT OFFICE.

ALBERT F. EMMONS, OF SWISSVALE, PENNSYLVANIA, ASSIGNOR OF ONE-HALF TO
I. LEONARD ARONSON, OF PITTSBURGH, PENNSYLVANIA.

GAME-BOARD.

1,312,315.

Specification of Letters Patent.

Patented Aug. 5, 1919.

Application filed December 28, 1917. Serial No. 209,209.

To all whom it may concern:

Be it known that I, ALBERT F. EMMONS, a citizen of the United States, and resident of Swissvale, in the county of Allegheny and 5 State of Pennsylvania, have invented a new and useful Improvement in Game-Boards; and I do hereby declare the following to be a full, clear, and exact description thereof.

My invention relates to a game apparatus, 10 and more particularly to game apparatus involving the principles of the well-known game of checkers.

The object of my invention is to provide a game which will stimulate war interest 15 and familiarize the players in the use of war terms, as well as entertain and amuse men in the ranks, whether in cantonments, in Y. M. C. A. huts, or even in the trenches.

In the accompanying drawing, Figure 1 20 is a plan view of a board for use in playing my improved game; Figs. 2 and 3 indicate some of the checkers or playing-pieces; Fig. 4 is an enlarged top view of one of the checkers with the insignia thereon; Fig. 5 25 is a like view showing a different insignia; Fig. 6 is a top view of one of the crowning-checkers of one side; and Fig. 7 a like view of one of the crowning-checkers of the opposing side.

30 In the drawing, the numeral 2 designates a suitable board formed of pasteboard, wood, papier-mâché, or any other suitable material; and on the board is laid out a square 3 made up of a number of smaller 35 squares, just as on the ordinary checkerboard, with the alternate squares of different colors. The middle section of squares on the board is designated as "no man's land," and on opposite sides of this are three 40 lines of squares designated as "first trench," "second trench," and "artillery," respectively. Outside of the main square 3 at opposite ends are what are designated as the "tanks," consisting of circular or other 45 shaped figures 4, some of said figures being plain while others have numerals, such as "20," "30," and "60."

At each side of the main square 3 are the 50 counters 5, which are termed "prison camps," and the counting is done by placing pins 6 in the different holes in the center for the keeping of the score.

The ordinary playing-pieces or checkers 7

have numerals on their bottom faces, and are placed with the numerals down or concealed in playing, and the upper faces of these checkers bear insignia of different nations; for instance, half the checkers will have the shield 8 as the insignia of the United States on their upper faces, and the other half will have the iron cross 9, the insignia of Germany,—the bottom faces, as stated above, bearing the numerals. However, one of the checkers bearing the insignia of Germany will have the iron cross 65 on both sides, and this for the purpose of having a "joker," which increases the score, and for the purpose of exciting greater interest in the game, as will more fully herein-after appear.

In Figs. 6 and 7 are shown the crowning-checkers 10 and 11, which are to be placed upon the circular figures 4, or "tanks," and these crowning-pieces have head-gear typical of the different countries; for instance, 75 the checker 10 has the hat typical of Uncle Sam, and the checker 11 has the helmet typical of the German. These crowning-pieces will, as stated, be arranged in a row outside of the main playing-square 3, and 80 will be taken from the circular figures 4 and placed on the checkers as they reach the "king" row, or "artillery" line, as it is indicated.

In the playing of the game, the checkers 7 85 are arranged in the same manner as in the ordinary game of checkers on the three rows of squares with the numbers face down or concealed so that the opponents do not know the value of the different checkers. The 90 game proceeds in the ordinary manner of playing checkers, and the object, of course, is to take as many "prisoners" as possible, and the higher the number on the "prisoners," the higher the count. When one of 95 the checkers reaches the "king" row, or as it is designated here under the title of "artillery," one of the crowning-pieces 10 or 11 is removed from one of the figures 4 or tanks and is placed on the checker which 100 has reached the "king" row.

In playing the game, the first "tank" counts double the score underneath the checker which has been crowned; the second counts, likewise, double the number; 105 and the third counts double the number

plus 20; the fourth, double the number plus 30, and the fifth, double the number plus 60.

As the checkers are taken, the score is entered up in the scores or "prison camps" at the side, and these "prison camps" have three rows of figures from zero to nine so that a score may be kept up to 999; for instance, suppose the first "prisoner" or checker taken has the figure 7 underneath, one of the pins is inserted in the hole alongside figure 7 in the first row to the left. The next "prisoner" taken may be number 8, whereupon the score is 15, and the peg is placed in figure 1 on the first row and a peg in figure 5 on the second row, which will indicate 15. Suppose the score stood 98 and the next "prisoner" is number 11, making the score 109, a peg is inserted at figure 1 in the first row,—a peg at zero in the second row,—and at 9 in the third row.

The first "soldier" to receive a crown or become a "tank" may be number 9,—this is doubled and added to the total score. The second "tank" is scored in the same way; the third "tank", however, after doubling the number on the bottom, has 20 added to it, as stated above; and so on, as above described, in case a player obtains a fourth or fifth "tank".

The interest in the game is accentuated by having one of the checkers on the German side with the iron cross top and bottom, and this checker is entitled the "joker", and if this checker is captured, it is characterized as "getting the Kaiser", and counts for 100 in the score.

The game is not over until the last checker or "tank" has been captured, and since the players must guess at the number underneath the checker, it is practically impossible to determine who is the winner until all the plays have been made.

In this crisis in the world's history, the men in the army camp, in the trench and back home, will find the game will afford not only refreshing and fascinating amusement, but will help all to forget the hardship of war in a pleasant pastime. The addition of figures and war terms, together

with the zest of the game, will afford recreation and relaxation.

What I claim is:

1. A game apparatus comprising a checker-board, a plurality of game-pieces having numbers on the bottom faces and bearing insignia on their upper faces characteristic of different countries, and one of said pieces having such insignia instead of a number on the bottom face.

2. A game apparatus comprising a checker-board, a plurality of game pieces having numbers on the bottom faces and bearing insignia on their upper faces characteristic of different countries, figures representing "tanks" arranged at the ends of the square forming the playing field and outside said field and game-pieces arranged to rest on said figures, said last-named game-pieces bearing the head-gear characteristic of different countries, and some of said figures having numbers thereon.

3. A game apparatus comprising a checker-board, a plurality of game-pieces having numbers on the bottom faces and bearing insignia on their upper faces characteristic of different countries, the different lines of squares on said board representing strategic military positions, such as "first trench," "second trench" and "artillery".

4. A game apparatus comprising a checker-board, a plurality of game-pieces having numbers on the bottom faces and bearing insignia on their upper faces characteristic of different countries, and scoring sections arranged at each side of said board comprising a rectangular figure made up of rows each having three squares, the top row containing ciphers, the second row ones, and so forth down to the tenth row of nines, and said squares having openings for the reception of pins.

In testimony whereof I, the said ALBERT F. EMMONS, have hereunto set my hand.

ALBERT F. EMMONS.
